UNITED STATES PATENT OFFICE.

CHARLES B. ULRICH, OF HOUGHTON, MICHIGAN.

VERTICAL FILE.

1,126,921.

Specification of Letters Patent.

Patented Feb. 2, 1915.

Application filed October 28, 1912. Serial No. 728,042.

To all whom it may concern:

Be it known that I, CHARLES B. ULRICH, a citizen of the United States, residing at Houghton, in the county of Houghton and State of Michigan, have invented a certain new and useful Improvement in Vertical Files, of which the following is a full, clear, concise, and exact description, reference being had to the accompanying drawings. forming a part of this specification.

My invention relates to an improved construction for facilitating the filing of papers of various descriptions, drawings, tracings, etc., in vertical position so that they may be readily accessible for inspection or removal when the file is open and held in compact form close together when the file is closed.

By my invention, drawings and tracings, whether of uniform size or different sizes and whether bound together or separate, may conveniently be supported in vertical position in the filing cabinet, in pockets, the nature of the support of the rods and pockets being such that when the device is closed the rods and upper edges of the pockets are close together, being separated by only such an amount as may be necessary to accommodate the usual thickness of papers or drawings that would be filed under one head, and the support for the pockets and rods is of such construction that when the mechanism is opened to inspect, remove or insert papers or drawings the pockets are in open position and the supporting rods are separated from each other automatically by a sufficient distance to completely separate the papers and drawings contained in the file, so that any desired paper or group of papers may be removed or inserted without interfering with any of the other contents of the file in any way. In this way a maximum amount of drawings and reference papers may be filed away and occupy a minimum amount of space when the file is closed without interfering with ready access to any of the contents of the file.

The several drawings illustrating my invention are as follows:

Figure 1 shows in vertical transverse sectional view a filing cabinet constructed in accordance with my invention. Fig. 2 is a plan view of the parts shown in Fig. 1. Fig. 3 is an enlarged detail view of one of the supporting brackets carried by the

mechanism of the cabinet. Fig. 4 is a front elevation of one of the pockets of the present invention. Fig. 5 is an end elevation of Fig. 4.

Similar numerals refer to similar parts throughout the several views.

My filing cabinet construction, as shown in Figs. 1 and 2, consists of a back piece 1, a bottom 2 and ends 3 secured together so as to form, in conjunction with the top and front, an inclosed receptacle when the top and front are in closed position. The front 4 is hinged to the bottom 2 at 5 and is provided near its ends with thin sheet metal sectors 6 which are secured to the front and extend just inside of the ends 3 of the cabinet when the front is open. Chains 7 are provided between the front 4 and the ends 3 outside of the sector 6 to limit the amount of opening of the front, these chains folding up inside of the cabinet between the sectors and the ends when the front is moved to its closed position. The top 8 of the cabinet is hinged to the back at 9 and is provided at each end with a pair of supporting links 10 and 11 extending between said end and the top of the adjacent end board 3 of the cabinet, these links being pivoted together so as to support the top in substantially vertical position and requiring a slight outward pressure to release them when it is desired to close the cover. Stops 12 formed on the links 10 prevent pressing the connecting points of the links inward beyond their supporting position.

Inside of each sector 6 and near the end of the front 4 a bracket 13 is secured to which one end of a "lazy tong" arrangement of metal bars 14 is pivoted, the other end of which is pivoted at 15 to a bracket 16 secured to the back board 1 near its upper edge. The bars 14 are, of course, similar and pivoted together at their mid points and at their ends, the effect of the construction being that the mid points or pivots are rigidly supported against vertical displacement for any position of the front board 4 relatively to the rest of the cabinet. At each of the mid points of the bars 14 metal supporting clips 17 are secured, being held in place by the same rivets which pivotally secure the bars 14 together. Each of these clips 17, as indicated more clearly in Fig. 3, has formed on its lower edge an outstanding flange 18 having therein two recesses for re-

90

ceiving the ends of the two supporting rods 19 and 20. The bars 14 at one end of the cabinet are held in proper relation to the corresponding bars at the other end of the cabinet by means of cross tubes 21 supported in line with the mid points of the corresponding bars 14 by rods 22 extending through them and riveted over the outside bars 14 to constitute the pivot connections for said bars, as indicated in Fig. 2. Each of the bars 19 and 20 is of such a length as to be readily inserted and removed from between the metal bars 14 into the supports or saddles formed by the flanges 18, said flanges being long enough so that the spring of the parts permitted by the cross-tubes 21 will not permit the bars 19 and 20 to drop out of place.

For the support of papers, drawings and the like, I employ pockets to be suspended from the rods 19 and 20. Each pocket, as shown in Figs. 4 and 5, is of any suitable flexible material as fabric of one kind or another and, in this case, the supporting rods 19 and 20 are secured in the upper edges of the pocket, the ends of said pocket are open and the mid portion of the pocket hangs loosely so as to accommodate itself to the thickness of papers or drawings to be filed in the pocket. In many cases, it is advisable to provide in addition to the fabric 25 reinforcing stays or springs 26 which may either be of metal or thin wood, the ends of these stays being contained in pockets 27 secured to the outside of the main portion 25 of the filing pocket, said springs being conformed so as to normally occupy a curved position, as indicated in Fig. 5, thus holding the fabric or material of the pocket 25 in position to engage with some amount of friction the papers or drawings contained in the pocket when the file is closed.

When the front board 4 of the cabinet is closed, the cross-bars and pockets are brought into close relation to each other and the entire contents of the cabinet are moved closely together in compact arrangement, as a result of which the maximum thickness of the cabinet from front to rear is available for filing papers, it not being necessary to have any unoccupied space between the papers when the cabinet is closed. In order to hold the front and top of the cabinet in closed position, a lock 30 may be secured to the upper edge of the front board 4 in position to receive a catch 31 carried by the under side of the cover 8 and when the catch is held in place in the lock the front board 4 cannot be opened and the cover 8 cannot be raised. The sectors 6 are provided so that the contents of the cabinet cannot project beyond the front board and be caught between the ends of the front board and the front edges of the ends of the cabinet when it is attempted to close the cabinet and,

furthermore; these sectors prevent interference between the chains 7 and the contents of the cabinet in placing the papers and drawings in the cabinet and in moving the front of the cabinet from its open to its closed position.

The file as a whole may be supported from the wall, as for example, by means of screws 32 or any equivalent supporting devices, or the file may be supported upon a standard from the floor, as desired.

It will be apparent that in carrying out my invention, when it is desired to construct a simple file, particularly adapted for temporary use, that the cabinet may be dispensed with, in which event the "lazy tong" arrangements are supported preferably from but one end by means of suitable devices so that they will constitute outwardly extending brackets disposed in substantially parallel arrangement, suitable cross-bars being provided, extending between similar points on the "lazy tong" arrangements, for reinforcing them and supporting the papers or drawings to be filed as described above.

While I have shown but two reinforcing rods 21 between the two "lazy tong" arrangements, it will be understood that as many of these cross-rods may be employed as desired and that they may consist either of the rod and tube arrangement particularly described, or any equivalent construction and, furthermore, the cloth pockets 25 may, if desired, be supported directly from these reinforcing rods 21 without the use of the supporting bars 19 and 20.

While I have shown my invention in the particular embodiment herein described, I do not, however, limit myself to this particular construction, as I may employ other equivalent constructions without departing from the spirit of my invention.

It will be noted that the closed bottoms of the pockets are above the bottom of the case or cabinet and are entirely free therefrom. This is a very important feature of the present invention because it permits of the sheets extending entirely to the bottom of the pocket in a smooth and straight condition, which would be impossible if the bottoms of the flexible pockets should strike the bottom of the case or cabinet and crumple or fold up thereon.

What I claim is:

1. In a file, the combination of a series of vertical pockets open at their upper ends, a series of transverse members from which the pockets are suspended, each pocket having one wall suspended from a transverse supporting member and its opposite wall suspended from the next successive transverse supporting member, said supporting members being movable in directions to front and rear of the series to open and close the

pockets, and means connecting the transverse members in series for separating and drawing together the transverse members.

2. In a file, the combination of a series of vertical pockets open at their upper ends, a series of transverse members from which the pockets are suspended, each pocket having one wall suspended from a transverse supporting member and its opposite wall suspended from the next successive transverse supporting member, said supporting members being movable in directions to front and rear of the series to open and close the pockets, and a "lazy tong" device connecting the transverse members in series to successively separate and draw together the transverse members by manipulation of the "lazy tong" device.

3. In a file, the combination of a series of vertical pockets open at their upper ends, a series of transverse members from which the pockets are suspended, each pocket having one wall suspended from a transverse supporting member and its opposite wall suspended from the next successive transverse supporting member, said supporting members being movable in directions to front and rear of the series to open and close the pockets, means connecting the transverse members in series for separating and drawing together the transverse members, and springs normally tending to hold the sides of the pockets together against the contents thereof.

4. In a file, the combination of a series of vertical pockets open at their upper ends, a series of transverse members from which the pockets are suspended, each pocket having one wall suspended from a transverse supporting member and its opposite wall suspended from the next successive transverse supporting member, said supporting members being movable in directions to front and rear of the series to open and close the pockets, a "lazy tong" device connecting the transverse members in series to successively separate and draw together the transverse members by manipulation of the "lazy tong" device, and springs normally tending to hold the sides of the pockets together against the contents thereof.

5. In a file, the combination of a series of vertical pockets open at their upper ends, a series of transverse members from which the pockets are suspended, each pocket having one wall suspended from a transverse supporting member and its opposite wall suspended from the next successive transverse supporting member, said supporting members being movable in directions to front and rear of the series to open and close the pockets, means connecting the transverse members in series for separating and drawing together the transverse members, and springs carried by the sides of the pockets

and tending normally to hold said sides together against the contents of the pockets.

6. A file comprising a series of vertical flexible pockets suspended from their tops and open at their upper ends for the introduction and removal of sheets, and spring means tending to force together the sides of each pocket to grip the contents of the pocket between its sides.

7. A file comprising a series of vertical flexible pockets suspended from their tops and open at their upper ends for the introduction and removal of sheets, and spring means exterior to each pocket and tending to force together the sides of each pocket to grip the contents of the pocket between its sides.

8. A file comprising a series of vertical flexible pockets open at their upper ends for the introduction and removal of sheets, and spring means carried upon the exterior of each pocket and tending to force together the sides of each pocket to grip the contents of the pocket between its sides.

9. A file comprising a series of vertical flexible pockets open at their upper ends for the introduction and removal of sheets, and upright bowed spring strips secured to the exterior of each side of each pocket and tending to force together the sides of the pocket to grip the contents thereof between said sides.

10. A file comprising a pair of substantially parallel "lazy tong" devices, clips hung upon the fulcrums of the crossed members of the two "lazy tong" devices, each clip having a pair of seats, cross bars having their ends supported in the corresponding seats of opposite clips, and pockets suspended from the cross bars, each pocket having one wall suspended from a cross bar on one clip and its opposite wall suspended from a cross bar on the next adjacent clip, whereby the pockets will be opened and closed by the opening and closing of the "lazy tong" devices.

11. A file having an upright flexible pocket open at its upper end and also suspended from its top, the closed bottom of the pocket being free and unsupported, and spring means pressing against the exterior of the opposite sides of the pocket and tending to force the sides of the pocket together to grip material therebetween.

12. A file having a series of flexible upright pockets open at their tops, and a "lazy tong" device from which the pockets are suspended and by which the pockets are opened and closed, the closed bottoms of the pockets being free and unsupported.

13. A file having a series of flexible upright pockets open at their tops, a "lazy tong" device from which the pockets are suspended and by which the pockets are opened and closed, the closed bottoms of

- the pockets being free and unsupported, and spring means tending to force together the opposite sides of each pocket to grip material in the pocket between the sides thereof.
- 5 14. A file comprising a case, a series of flexible upright pockets open at their tops, and a "lazy tong" device mounted within the case and from which the pockets are suspended and by which the pockets are opened
- 10 and closed, the closed bottoms of the pockets

being above and out of contact with the bottom of the case.

In witness whereof, I hereunto subscribe my name this 26th day of October A. D., 1912.

CHARLES B. ULRICH.
